UNITED STATES PATENT OFFICE.

LESLIE S. HACKNEY, OF ST. PAUL, MINNESOTA.

DRAFT APPLIANCE FOR PLOWS.

1,219,636.

Specification of Letters Patent. Patented Mar. 20, 1917.

Application filed August 25, 1913. Serial No. 786,438.

To all whom it may concern:

Be it known that I, LESLIE S. HACKNEY, a citizen of the United States, residing at St. Paul, in the county of Ramsey and State of Minnesota, have invented an Improved Draft Appliance for Plows, of which the following is a specification.

My invention relates to an improved draft appliance for plows.

10 Its object is to provide means for attaching the beam of a plow to a draft frame to permit a free vertical movement within predetermined limits, of said beam.

15 A further object is to provide in a device of this kind, means for exerting a yielding downward pressure upon the end of a plow beam and also means for moving said beam to elevate the same or detach it from the draft frame.

20 In the drawings, Figure 1 illustrates a portion of a draft frame with a plow attached thereto by means of my improved device; Fig. 2 is a plan view showing my device employed to connect a plurality of 25 plows with a draw-bar and Fig. 3 is an enlarged detail sectional view taken on the line 3—3 of Fig. 2.

Referring to the accompanying drawings, I have used the reference numeral 10 to indicate the frame of a draft vehicle and 11 the draw-bar thereon. The numeral 12 designates the body of a plow and 13 the beam, said beam being provided with a gaging device such as the wheel 14 revolvable upon 30 the vertically adjustable arm 15 near the end of said beam. A plurality of plows are connected with the bar 11 and operated identically; therefore, a description of one plow and its draft appliance will suffice for all.

40 A bracket 16, having rearwardly extended branches 17 formed with vertical bearing surfaces 18, is secured to the draw-bar 11. A yoke 19 is provided at the end of the plow beam 13, said yoke being supplied with a 45 pair of bearing plates 20 adapted to fit snugly between the bearing surfaces 18 of the bracket 16. A pin 21, extending transversely through the bearing plates 20 of said yoke, is pivoted and slides at its ends in the 50 opposed vertical grooves 22 in the bracket. To the shaft 23, revolvable upon the draw-bar 11, is fixed a forked lever 24 having upper and lower arms 25 and 26. This lever 24 is located between the branches of said 55 bracket and the lower arm 26 is adapted to engage and raise the pin 21 to elevate the plow beam 13 secured thereto. Said arm 26

is also adapted, when further elevated, to detach the beam from the bracket and to remove the pin 21 from the grooves 22. A 60 spring 27 is interposed between the pin 21 and upper arm 25 to exert a yielding downward pressure upon the pin when said arm is lowered. A socket 28, formed in the arm 25, receives and retains the upper end of the 65 spring 27, when compressed, and a guide rod 29, for said spring, is slidably mounted at its upper end in said arm and detachably secured to the pin 21 at its lower end. The shaft 23 may be turned by hand or by power 70 and locked in any convenient manner. I prefer, in turning the same by hand, to employ a worm segment 30 on the shaft 23 adapted to mesh with a worm 31 mounted upon and driven by the shaft 32 which is 75 supplied with a hand wheel 33 for turning the same.

In use, when the parts are in position illustrated in Fig. 3, the forward ends of the plow beams 13 fall and rise freely in response to the movements of the supporting gage wheels 14. When plowing in hard ground, it is often desirable to exert a yielding downward pressure upon the ends of the 80 plow beams to retain the plow bodies in the ground and this is accomplished simultaneously in all of the plows by turning the shaft to lower the levers 24 thereby depressing the arms 25, which operating through the springs 27, bear downward upon the pins 21 in the 85 plow beams. The ends of said plow beams are simultaneously lifted by turning the shaft 23 to swing the levers 24 upward, the arms 26 on said levers being arranged to engage and raise the pins 21, and continued 90 rotation of said shaft results in lifting the pins 21 from the grooves 22 in the brackets 17, thereby detaching the plow beams from the draft frame.

Having described my invention, what I 100 claim as new and desire to protect by Letters Patent, is:

1. In a draft appliance for plows, the combination with a plow beam having a gaging device and a draft frame therefor, of a 105 support secured to the frame, the forward end of said plow beam having a pivotal and vertically slidable connection with said support, and adjustable means to confine the vertical movements of said plow beam between certain limits, said means being also adapted to depress said plow beam and raise the same.

2. In a draft appliance for plows, the

combination with a plow beam having a gaging device and a draft frame therefor, of a support secured to the frame, said plow beam being slidable vertically on said support and free to rise and fall thereon, and arms fixed with respect to each other but adjustable on said support to limit the movements of said beam, one of said arms being adapted to raise said beam and detach the same from said support.

3. In a draft appliance for plows, the combination with a plow beam having a gaging device and a draft frame therefor, of a support secured to the frame, said plow beam being slidable vertically on said support and free to rise and fall thereon, arms integral with each other but adjustable on said support to limit the upward and downward movements of said beam, and means in connection with one of said arms for exerting a yielding downward pressure upon said beam.

4. In a draft appliance for plows, the combination with a plow beam having a gaging device and a draft frame therefor, of a support carried by said frame, a transverse horizontal pivot in said beam, slidable vertically on said support, a lever having an upper and lower arm, said arms being located on opposite sides of said pivot and spaced apart to allow said pivot to move between them and means for operating said lever to engage the pivot and raise said beam.

35 5. In a draft appliance for plows, the combination with a plow beam having a gaging device and a draft frame therefor, of a support carried by said frame, a transverse horizontal pivot in said beam, slidable vertically on said support, a lever having an upper and lower arm, said arms being located on opposite sides of said pivot and spaced apart to allow said pivot to move between them and means for operating said lever to engage the pivot and raise said beam and also to detach the beam from said support.

6. In a draft appliance for plows, the combination with a plow beam having a gaging device and a draft frame therefor, of a bracket formed with two branches and carried by said frame, said bracket having bearing surfaces with a vertical groove in each, yokes on said beam having bearing plates adapted to fit within said bearing surfaces, pins in said plates adapted to engage and travel in said grooves, a lever having an upper and lower arm, said arms being located on opposite sides of said pin and spaced apart to allow said pin to move between them and means for operating said lever to engage the pin and raise said beam.

7. In a draft appliance for plows, the

combination with a plow beam having a gaging device and a draft frame therefor, of a bracket formed with two branches and carried by said frame, said bracket having bearing surfaces with a vertical groove in each, yokes on said beam having bearing plates adapted to fit within said bearing surfaces, pins in said plates adapted to engage and travel in said grooves, a lever having an upper and lower arm, said arms being spaced apart and located on opposite sides of said pin, a spring interposed between said pin and upper arm and means for operating said lever to engage the pin and raise said beam and also to exert a yielding downward pressure thereon.

8. In a draft appliance for plows, the combination with a draft frame, of a plurality of supports carried by said frame, plow beams carrying plow bodies, gages for the beams, transverse horizontal pivots, free to slide vertically on said supports and connecting the same with the several plow beams, a revolute shaft adjacent to said supports, levers on said shaft, each lever having upper and lower arms located on opposite sides of a pivot and spaced apart to allow said pivot to move between them and means for turning said shaft to simultaneously raise said beams.

9. In a draft appliance for plows, the combination with a draft frame, of a plurality of supports carried by said frame, plow beams carrying plow bodies, gages for the beams, transverse horizontal pins, slidable vertically on said supports and connecting the same with the several plow beams, a lever adjacent to each support having arms adapted to engage above and below a pin, said arms permitting said pin to move freely therebetween and means for turning said levers.

10. In a draft appliance for plows, the combination with a draft frame, of a plurality of supports carried by said frame, plow beams carrying plow bodies, gages for the beams, transverse horizontal pins, slidable vertically on said supports and connecting the same with the several plow beams, a lever adjacent to each support having arms adapted to engage above and below a pin, said arms permitting said pin to move freely therebetween, a spring interposed between the upper arm of each lever and the pin adjacent thereto and means for turning and locking said levers.

In testimony whereof, I have signed my name to this specification in the presence of two subscribing witnesses.

LESLIE S. HACKNEY.

Witnesses:

F. C. CASWELL,
LOUIS JOHNSON.

It is hereby certified that in Letters Patent No. 1,219,636, granted March 20, 1917, upon the application of Leslie S. Hackney, of St. Paul, Minnesota, for an improvement in "Draft Appliances for Plows," an error appears in the printed specification requiring correction as follows: Page 2, line 91, claim 8, for the word "rivet" read *pivot*; and that the said Letters Patent should be read with this correction therein that the same may conform to the record of the case in the Patent Office.

Signed and sealed this 10th day of April, A. D., 1917.

[SEAL.]

F. W. H. CLAY,

Acting Commissioner of Patents.
